UNITED STATES PATENT OFFICE.

KINGSLEY R. OLMSTED, OF CHICAGO, ILLINOIS.

REACTION PROPELLER-WHEEL.

SPECIFICATION forming part of Letters Patent No. 230,566, dated July 27, 1880.

Application filed April 5, 1880. (No model.)

To all whom it may concern:

Be it known that I, KINGSLEY R. OLMSTED, of the city of Chicago, county of Cook, and State of Illinois, have invented certain Im- 5 provements in Reaction Propeller-Wheels, of which the following is a specification.

The object of my invention is to utilize the reactionary power of steam, compressed air, or any like motor, when ejected from the blades 10 of a four-bladed screw-propeller under water, to propel vessels and boats, and to do this in a simple, direct, and comparatively inexpensive manner, and to reverse the action of the propeller at will. I effect this object by means 15 of the parts and combination of parts herein- after described with reference to the accompanying drawings, in which—

Figure 1 represents an elevation of a screw- 20 propeller in connection with a portion of the hull of a boat; Fig. 3, a transverse vertical section of a screw-propeller, as indicated by the broken line in Fig. 1; Fig. 2, a longitudinal vertical central section of the whole apparatus, and Fig. 4 a detail perspective of the 25 tabular valve *b*.

A is a lever pivoted in bracket, *B*, which is fastened upon cylinder *C*, and its foot is seated in a depression in the end of valve-shaft.

D is the outer bearing for the journal *i* of 30 the propeller-wheel; *E*, the hub of the same, and *v v w w* its four blades.

b is the tubular sliding valves, seated in a suitable chamber in the center of the hub *E*, and it is provided upon its outer surface with 35 a slot, *S*, of sufficient depth and length, in order that its lengthwise motion may be limited by the set-screw *h*, inserted into it through the hub *E*, and the set-screw will prevent the valves from revolving in the hub, and cause it 40 to revolve with it. The valve is also provided with two sets or pairs of port-holes, *d d* and *c c*, to correspond with the ports *f f* in the two pairs of blades *v v* and *w w*, so that when the valve is in one extreme position steam will be admitted into one pair of blades to drive the boat forward; but when it is in the other extreme position steam will be admitted into the other pair of blades to drive the boat backward.

The valve *b* is operated by the valve-shaft 45 *g*, which is provided with a stuffing-box, *p*,

upon one end of cylinder *C*, while the other end is attached to the valve itself.

The steam is admitted into cylinder *C* through the induction-pipe *a*, and a steam-tight connection is made between it and the sleeve *n* by means of the stationary nipple *o*, and the sleeve allows the passage of the steam through the shell or hull *D* of the vessel, and jam-nuts *m* and *l* on either side hold the sleeve firmly in position, and the connection is made 55 between the sleeve and hub *E* of the wheel by means of revolving nipple *J*, and the joint between that nipple and the sleeve is made steam-tight by means of the stuffing-box *k*.

e indicates one or more vent-holes through 60 the back end of the valve *b*, for the passage of steam to balance the same, so that it will be in a state of equipoise, and can be moved with equal force either way.

Perforations *g g* and *u u* are made in the 65 sides of the ends of the blades for the discharge of the steam, so that jets of steam shall issue from the blades perpendicular to the axis of the wheel and tangential to the circles described by the blades, and the said perforations are so arranged, as shown in Fig. 3, that the jets from the pair of blades *w w* shall strike the water in exactly opposite directions from those issuing from the pair of blades *v v*.

It may be seen from Fig. 2 that my devices 70 can be operated from within the vessel, that my cylinder *C* does not revolve, and that the bearing for my screw-propeller, the journal *i*, and the revolving nipple *J* are outside of the boat and in the water, where they are cooled 75 and lubricated thereby.

The only motion the valve *b* has in relation 80 to hub *E* is the back and forward one to start and reverse the propeller, and therefore it will bear service a long time, which would not 85 be the case if it revolved in the hub itself.

What I claim as my invention, and desire to 90 secure by Letters Patent, is—

1. A screw-propeller having two pairs of blades, the blades of each pair being in the 95 same straight line, and provided with ports *f* and side orifices, *g* and *u*, and in combination with sliding valve *b*, having two pairs or sets of ports therein, so arranged that by moving the valve forward or backward steam may be 100

admitted into either pair of blades at will, substantially as described.

2. The sliding valve *b*, provided with one or more vent-holes, *e*, in its outer end, in combination, with its chamber in hub *E*, when that chamber is provided with a sufficient steam-space behind the valve adapted to render the valve so balanced as to be moved with an equal amount of force either way, substantially as described.

3. The combination of the valve-rod *q* and

the lever *A*, having fulcrum *B*, by which the same may be operated, and the sliding valve *b*, with its two sets of port-holes *c* and *d*, adapted to admit steam into either pair of the 15 blades of the propeller at will, as required, substantially as described.

KINGSLEY RAY OLMSTED.
